UNITED STATES PATENT OFFICE

162,253

AUTOMOBILE FENDER

Frank Stanley, Detroit, Mich., assignor to Chrysler Corporation, Highland Park, Mich., a corporation of Delaware

Application August 13, 1949, Serial No. 4,480

Term of patent 7 years

(Cl. D14—6)

To all whom it may concern:

Be it known that I, Frank Stanley, a citizen of the United States, residing in the city of Detroit, county of Wayne, and State of Michigan, have invented a new, original, and ornamental Design for an Automobile Fender, of which the following is a specification, reference being had to the accompanying drawing, forming part thereof, in which:

Fig. 1 is a side elevation of a fender incorporating my novel design;

Fig. 2 is a top plan view of the fender;

Fig. 3 is an end elevation of the fender; and

Figs. 4, 5, 6 and 7 are sections taken on the lines 4—4, 5—5, 6—6 and 7—7 of Fig. 1.

The dominant features of my design are shown in full lines.

I claim:

The ornamental design for an automobile fender, substantially as shown and described.

FRANK STANLEY.
